GRID CONSTRUCTION

James H. Cone, Roseland, N. J., assignor to National Union Radio Corporation, Newark, N. J., a corporation of Delaware

Application April 4, 1931, Serial No. 527,649

7 Claims. (Cl. 250—27.5)

This invention relates to a grid construction, more particularly that of the control grid, of a vacuum tube.

It is known to those skilled in the art that problems in distortion and cross-talk occasioned in tubes used in the radio frequency stages of a receiving set, are manifested in self-rectification produced in the tube. A simple explanation of these problems is that they are caused by a sudden change in the plate current, with a consequent change in the mutual conductance of the tube. Since the accepted definition of mutual conductance is the slope of the plate current curve, a sudden change in the slope thereof will cause distortion or cross-talk.

In an attempt to overcome these difficulties, tubes with exponential characteristics have been designed, as for example reference may be made to an article by Ballantine and Snow, published in the December 1930 issue (vol. 18, No. 12) of Proceedings of The Institute of Radio Engineers, pages 2102-27.

It has been discovered that the true exponential characteristics of a tube can be expressed by a formula which would give a true exponential curve.

It is an object of my invention to provide a grid construction having the turns thereof spaced, so that the plate current and mutual conductance of a tube embodying the same will follow approximately a true exponential curve.

Another object is to provide such a control grid of which the turns thereof are symmetrical.

A further object is the provision of a grid construction, having extreme simplicity yet adapted to produce a tube with exponential characteristics.

Other objects of the invention will manifest themselves as the description proceeds.

In accordance with my invention there is provided a grid, the turns of which are symmetrically arranged and spaced according to my formula. When a grid conforming to this construction is mounted in the vacuum tube it will produce characteristics which will conform substantially to a true exponential curve.

In the accompanying drawing:

Fig. 1 schematically represents an enlarged plan view of a control grid embodying the invention;

Fig. 2 is an end view of the grid shown in Fig. 1;

Fig. 3 is a sectional view diagrammatically illustrating the arrangement of the cathode, grid,

and plate of a three element tube embodying the invention;

Fig. 4 is a view similar to Fig. 3 illustrating the invention as applied to a tetrode type tube; and

Fig. 5 is a graph showing true exponential curves of plate current and mutual conductance obtained by using a grid having the construction shown in Fig. 1.

It has been discovered by prior workers of the art that a true exponential curve may be expressed by the following formula:

$$I_p \text{ or } G_m = K e^{a E_g}$$

Where a and K are constants for a given construction.

e the base of natural logarithms.

E_g the value of the applied control grid voltage.

However, remote cut-off tubes heretofore known do not follow this curve, as for example the Ballantine 551-E tube discussed in the above mentioned article.

My invention contemplates that if the turns of the grid were spaced according to my formula, a tube could be made with truly exponential plate current and mutual conductance curves when plotted against applied grid voltages. I developed such a formula for the space between turns, said formula taking the following general form:

$$n = K_1 + K_2 \left(\frac{N}{2} \right)^a$$

K_1 = space between wire for first turn.

K_2 = empirical constant.

N = number of turns from end of grid.

a = constant exponent.

The term "exponential" when used in relation to the grid spacing of a given tube is not mathematically correct, since the exponent " a " becomes a constant for any given grid. However, from the standpoints of grids in general, my equation is exponential since " a " is a variable.

This will give us a grid with the wires widely spaced at one end and closely spaced at the other. It is evident that the grid should be symmetrical; therefore, both halves of the active grid length should be complementary to each other, so that a complete grid starting with the center turn would have each adjacent turn on one side complementary to a corresponding adjacent turn on the other side.

In applying

$$n = K_1 + K_2 \left(\frac{N}{2} \right)^a$$

55

the form of grid shown in Fig. 1 was designed. As is common practice in the construction of control grids, the wire 1 is spirally wound about a pair of support wires 2, separated at their ends by a 5 cylindrical spacing element 3 provided with apertures 4, through which the ends of the support wires extend. The respective turns of the grid wire may be welded to the support wires, or fastened in any other approved manner. The spacing 10 ing of the turns, derived from the

$$n = K_1 + K_2 \left(\frac{N}{2} \right)^a$$

are as follows:

15	$s = \text{wire spacing}$
20	1st 11 turns $s = .0120$
	12th turn $s = .0124$
	13th turn $s = .0156$
25	14th turn $s = .0242$
	15th turn $s = .0410$
	16th turn $s = .0690$
	17th turn $s = .1100$
	18th turn $s = .1100$
30	19th turn $s = .0690$
	20th turn $s = .0410$
	21st turn $s = .0242$
	22nd turn $s = .0156$
	23rd turn $s = .0124$
	Last 11 turns $s = .0120$

Total turns 34
Grid length .813"

The grid wire diameter, grid diameter and plate 35 or anode distance to grid will not affect the shape of the curve but will shift the curve with respect to the coordinates, nor will a change in cathode or anode area change the shape of the curve, as shown by the constant "B" above.

40 Referring to Figs. 3 and 4 the tube elements are diagrammatically illustrated and show the invention applied to a three element and a four element type tube, respectively. The filament 10 is enclosed within a cathode sleeve 11, and adjacent to the cathode is placed the grid 12, having the turns thereof variably spaced in accordance with my formula. In Fig. 3 the plate is designated by the reference character 13, while in Fig. 4 it is identified as 15. The shield, and shield grid, being electrically connected, are designated by the single reference 14. As the function of these elements is well understood in the art, there is no occasion to show any circuit arrangements, nor further detail of construction.

55 From the foregoing description it is obvious that the advantage of a tube embodying the invention will have greatly reduced rectification from the standpoint that whatever rectification takes place it will be more or less uniformly 60 distributed or spread along the exponential curve, and in that manner distributed so as to be practically unnoticeable during the functioning of the tube.

It is not intended to be limited by the exact 65 disclosure set forth as variations and substitutions may be made within the range or limits defined by the claims. For example, it may be found advantageous to reverse the spacing of the turns of the grid so that the central turn has 70 a small pitch which becomes increasingly coarser toward the ends. Furthermore, for various reasons it may be desirable to make the grid flat instead of cylindrical in shape. All such modifications are contemplated by me as come within 75 the scope of the claims.

What is claimed is:

1. An electron discharge device comprising an anode, an emitter and a grid surrounding the emitter within the anode, said grid being a control grid and having a wider mesh at the central portion than at the ends, the mesh of the two halves of said grid being complementary with respect to the central point thereof and the spacing n of the turns of each half being determined by the following formula:

$$n = K_1 + K_2 \left(\frac{N}{2} \right)^a$$

where

K_1 =space between wire for first turn

K_2 =empirical constant

N =number of turns from end of grid

a =constant exponent

20 said spacing giving the tube a mutual conductance-grid bias curve which is practically a straight line when plotted on semi-log paper.

25 2. An electron discharge device comprising an anode, an emitter, a plurality of grids surrounding the emitter within the anode, the spacing n of the turns of one of said grids being in accordance with the formula having the following general form:

$$n = K_1 + K_2 \left(\frac{N}{2} \right)^a$$

where

K_1 =space between wire for first turn

K_2 =empirical constant

N =number of turns from end of grid

a =constant exponent

30 said spacing giving the tube a mutual conductance-grid bias curve which is practically a straight line when plotted on semi-log paper.

35 3. A grid construction comprising a grid having a wider mesh at the central portion than at the ends, the meshes of the two halves of said grid being complementary with respect to the central portion thereof and the spacing n of the turns of each half being determined by the following formula:

$$n = K_1 + K_2 \left(\frac{N}{2} \right)^a$$

40 where

K_1 =space between wire for first turn

K_2 =empirical constant

N =number of turns from end of grid

a =constant exponent

45 4. A grid construction comprising a grid continuously wound and having the form of a complete enclosing circuit, the turns of said grid being symmetrically arranged and uniform in diameter from end to end, the spacing n of the turns of said grid being in accordance with the following formula:

$$n = K_1 + K_2 \left(\frac{N}{2} \right)^a$$

50 where

K_1 =space between wire for first turn

K_2 =empirical constant

N =number of turns from end of grid

a =constant exponent

55 5. An electron discharge device comprising an anode, an emitter and a grid surrounding the emitter within the anode, said grid being a con-

5 trol grid continuously wound and having the form of a complete enclosing circuit, the turns of said grid being symmetrically arranged and uniform in diameter from end to end, the spacing n of the turns of said grid being of wider mesh at the central portion than at the ends and in accordance with the formula having the following general form:

$$10 n = K_1 + K_2 \left(\frac{N}{2} \right)^a$$

where

K_1 =space between wire for first turn
 K_2 =empirical constant
15 N =number of turns from end of grid
 a =constant exponent

6. An electron discharge device comprising an anode, an emitter and a grid surrounding the emitter within the anode, said grid being a control grid cylindrically shaped and having the turns thereof symmetrically arranged and uniform in diameter from end to end, the spacing n of the turns of said grid being in accordance with

the formula having the following general form:

$$n = K_1 + K_2 \left(\frac{N}{2} \right)^a$$

where

K_1 =space between wire for first turn
 K_2 =empirical constant
 N =number of turns from end of grid
 a =constant exponent

7. An electron discharge device comprising an anode, an emitter and a grid surrounding the emitter within the anode, the spacing n of the turns of said grid being in accordance with the formula having the following general form:

$$10 n = K_1 + K_2 \left(\frac{N}{2} \right)^a$$

where

K_1 =space between wire for first turn
 K_2 =empirical constant
20 N =number of turns from end of grid
 a =constant exponent
